UNITED STATES PATENT OFFICE

GEORGE R. ADAMS, OF LOS ANGELES, CALIFORNIA, ASSIGNOR TO L. C. SACHS, OF
LOS ANGELES, CALIFORNIA

DESIGN FOR A DOOR CATCH

Application filed February 24, 1930. Serial No. 34,629. Term of patent 3½ years.

To all whom it may concern:

Be it known that I, GEORGE R. ADAMS, a citizen of the United States, residing at Los Angeles, in the county of Los Angeles and State of California, have invented a new, original, and ornamental Design for a Door Catch, of which the following is a specification, reference being had to the accompanying drawing, forming part thereof.

Fig. 1 is a perspective view of the door catch embodying my new design.

Fig. 2 is a side elevational view.

Fig. 3 is an end elevational view.

Fig. 4 is a plan view.

I claim:

The ornamental design for a door catch, as shown.

GEORGE R. ADAMS.
